US0D1064236S

(12) **United States Design Patent** (10) **Patent No.:** **US D1,064,236 S**
(45) **Date of Patent:** **** Feb. 25, 2025**

(54) **CEILING FAN**

(71) Applicant: **HUNTER FAN COMPANY**,
Memphis, TN (US)

(72) Inventor: **Brian Earl Lintner**, Memphis, TN
(US)

(73) Assignee: **Hunter Fan Company**, Memphis, TN
(US)

(**) Term: **15 Years**

(21) Appl. No.: **29/813,954**

(22) Filed: **Nov. 2, 2021**

(51) **LOC (15) Cl.** **23-03**

(52) **U.S. Cl.**

USPC **D23/385**

CLAIM

The ornamental design for a ceiling fan as shown and described.

DESCRIPTION

FIG. 1 is a top perspective view of a ceiling fan, showing my new design.

FIG. 2 is a bottom perspective view thereof;

FIG. 3 is a bottom view thereof;

FIG. 4 is a top view thereof;

FIG. 5 is a right side view thereof;

FIG. 6 is a left side view thereof;

FIG. 7 is a front view thereof; and,

FIG. 8 is a rear view thereof.

Portions of the ceiling fan and ceiling fan environment shown in broken lines form no part of the claimed design. The ceiling fan blades are shown with a symbolic break, which forms no part of the claimed design.

1 Claim, 8 Drawing Sheets
